US00D949130S

(12) **United States Design Patent** (10) **Patent No.:** **US D949,130 S**
(45) **Date of Patent:** **** Apr. 19, 2022**

(54) **HEADPHONE**

(71) Applicant: **BRAGI GmbH**, Munich (DE)

(72) Inventor: **Arne D. Loermann**, Munich (DE)

(73) Assignee: **BRAGI GmbH**, Munich (DE)

(**) Term: **15 Years**

(21) Appl. No.: **29/667,857**

(22) Filed: **Oct. 25, 2018**

4,334,315 A 6/1982 Ono et al.
D266,271 S 9/1982 Johanson et al.

(57) **CLAIM**

The ornamental design for a headphone, as shown and described.

DESCRIPTION

FIG. 1 is a perspective view of an headphone in accordance with the present invention;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines shown in FIGS. 1-3 and 5-7 illustrate portions of the headphone that form no part of the claimed design.

1 Claim, 2 Drawing Sheets
